(57) **CLAIM**

We claim, the ornamental design for a luminaire with mounting stanchion, as shown and described.

DESCRIPTION

FIG. 1 is a perspective view of a luminaire with mounting stanchion, showing our new design;

FIG. 2 is a perspective view of a luminaire with mounting stanchion in another embodiment of the invention, showing our new design;

FIG. 3 is a front elevation view of the design shown in FIG. 1;

FIG. 4 is a front elevation view of the design shown in FIG. 2; and,

FIG. 5 is a side elevation view of the design shown in FIG. 1 and FIG. 2, the opposite sides of which are mirror images hereof.

The luminaire is shown broken away in FIGS. 1 and 3 to show indeterminate length.
